CLAIM

I claim the ornamental design for a bin, as shown and described.

DESCRIPTION

FIG. 1 is a front/left/top perspective view of a bin;
FIG. 2 is a rear/right/bottom perspective view thereof;
FIG. 3 is a front elevational view thereof (a rear elevational view would be a mirror image thereof);
FIG. 4 is a right side elevational view thereof (a left side elevational view would be a mirror image thereof);
FIG. 5 is a top plan view thereof; and,
FIG. 6 is a bottom plan view thereof.
The broken lines depict portions that form no part of the claimed design.
